COMBINED WATCH BRACELET AND LAPEL WATCHCASE OR SIMILAR ARTICLE

Benjamin Khalaf, Brooklyn, N. Y.

Application March 7, 1950, Serial No. 8,372

Term of patent 3½ years

(Cl. D45—4)

To all whom it may concern:

Be it known that I, Benjamin Khalaf, a citizen of the United States, residing at 100 East 21st Street, in the county of Kings and State of New York, have invented a new, original, and ornamental Design for a Combined Watch Bracelet and Lapel Watch Case or Similar Article, of which the following is a specification, reference being had to the accompanying drawing, constituting a part hereof.

Fig. 1 is a front perspective view of a combined watch bracelet and lapel watch case, showing my new design the portions of the bracelet member, shown in full lines, being repeated throughout the length of said member,

Fig. 2 is a front perspective view with the cover in open position.

I claim:

The ornamental design for a combined watch bracelet and lapel watch case or similar article, substantially as shown and described.

BENJAMIN KHALAF.
